UNITED STATES PATENT OFFICE.

ROBERT McA. LLOYD, OF NEW YORK, N. Y., ASSIGNOR, BY MESNE ASSIGNMENTS, TO
GENERAL VEHICLE COMPANY, INC., A CORPORATION OF NEW YORK.

FREIGHT-TRUCK.

1,211,949

Specification of Letters Patent.

Patented Jan. 9, 1917.

Application filed September 12, 1913. Serial No. 789,563.

To all whom it may concern:

Be it known that I, ROBERT McA. LLOYD, a citizen of the United States, residing at New York, in the county of New York, State of New York, have invented certain new and useful Improvements in Freight-Trucks, of which the following is a specification.

My invention relates to freight and baggage trucks and particularly to those trucks adapted for use on freight and baggage platforms. In such trucks as heretofore constructed, it has been common to supply a platform at one or both ends of the truck upon which the operator may ride in standing position. Located within reach of the operator are the controlling handles or levers. Generally these controlling handles are two in number, one for steering the vehicle and the other for operating the controller. Prior to my invention it was common to mount the handles in such a way that they moved in horizontal planes. It has been found that such a construction is open to serious objection. Standing upright with his hands on the controlling handles the operator is unsupported except as he stands on the platform, unless some additional supporting means are provided. In turning corners there is a tendency for the operator to be thrown from the platform and a still greater tendency for the movement of his body, even if he is not thrown from the platform, to operate one or both of the controlling handles, leading to more or less disastrous results. To overcome this trouble it has even been suggested to supply a stationary rest against which the operator may lean when standing on the platform.

The object of my invention is to overcome this difficulty without providing any additional structure. I do this by pivoting the controlling handles in such a way that they move only in vertical planes, locating one controlling handle adjacent each side of the platform, spacing them apart such a distance as to conveniently receive the operator's body, and giving them considerable strength in a horizontal direction. Preferably the handles are pivoted to an end portion of the frame of the vehicle. With such a construction, the operator may support himself by the handles while standing on the platform and by their aid resist any force tending to throw him from the plat-

form without danger of moving the handles from the proper positions. It is unnecessary, therefore, to provide any additional rest for the operator's body. Furthermore, the handles are always moved against the weight of the operator. With horizontally movable handles the operator often has difficulty in moving the handles when turning at any considerable speed due to the force tending to throw him from his position. Operators make it a practice when operating a machine with horizontally movable handles, to slow down as a turn is approached, in order that they may not lose control on the turn. With vertically movable handles, on the other hand, the handles are moved against the constant weight of the operator, irrespective of the speed, and there is no necessity to reduce the speed at the turn. In practice it has been found that a truck with vertically movable handles covers a considerably greater distance each day than a similar truck with horizontally movable handles, due to the small saving in time at each turning.

In the accompanying drawings which form a part of this specification, I have illustrated one construction involving my invention.

Figure 1 is a plan view of a truck to which my invention is applied, partly in section. Fig. 2 is an elevation, partly in section, of the same truck.

Attached to the platform 1 of the truck are the guides 2. Within these guides are carried the portions 3 of the tie member 4. The tie member at its outer ends carries the axle spindles of the wheels. One or both pairs of axle-spindles may be mounted on knuckle joints 6 for steering. In the construction I have illustrated the single pair of wheels 5 is mounted for steering; each knuckle is provided with an arm 7 the two arms being joined together by the rod 8. A shaft 9 is mounted on the frame of the vehicle and carries an arm 10. Between the arm 10 and the rod 8 is the connecting rod 11, preferably connected to both the arm 10 and the rod 8 through universal connections. At the opposite end of the vehicle the shaft 9 is provided with another arm 12. A rod 13 extends substantially vertically upward from this arm 12 and is pivoted to the steering lever 14. The steering lever 14 is pivoted on a horizontal pivot

to the post 15, the post 15 forming a part of the end structure of the vehicle. This steering lever 14 is located adjacent one side of the operator's platform 16 which is carried by the platform 1 of the vehicle. It will be apparent from this that as the steering handle 14 is moved upwardly or downwardly the wheels 5 are turned in one direction or the other.

10 The vehicle I have illustrated is electrically operated. The motor 17 and battery box 18 are carried under the platform 1 in any suitable manner. The controller 18^a for the motor is mounted at the operator's 15 end of the vehicle and may be of any desired construction. This controller is operated by the lever 19 from which extends the substantially vertical rod 20. The rod 20 is pivoted at its upper end to the controller lever 21 which, like the steering lever 14, is pivoted on a horizontal pivot to one of the uprights at the end of the vehicle, and is located adjacent the opposite side of the platform 16. A spring 22 returns 25 the controller to any desired neutral position. The operating levers 14 and 21 are spaced apart a sufficient distance to allow for the reception of the operator's body between them. It will be seen from this that the controller is also operated by a handle moving in a vertical plane and that any swaying of the operator's body, as when rounding a corner, is incapable of moving the operating handles 14 and 21. Furthermore, 30 the operator may use these handles to steady himself on his platform and always operates them against his own constant weight.

Preferably the platform carries a brake 40 lever 23 operating the brakes 24 in any desired manner. Preferably, also a circuit breaker 25 is located on the underside of the platform 16 and so connected to the brake lever 23 as to interrupt the circuit 45 whenever the brakes are applied.

It will be understood from the above that the objections to the constructions heretofore common have been overcome by my invention.

50 My invention is obviously subject to numerous modifications. The principal fea-

ture of my invention, as will be understood, is providing for the movement of at least one controlling handle in a vertical plane in order that the movement to which the operator's body is subject, is ineffective to displace the handle, and in order that the operator may steady himself thereby.

What I claim as new and desire to secure by Letters Patent of the United States, is:—

1. The combination in a freight truck, of a platform at one end thereof upon which the operator stands, and an operating lever pivoted to the truck above and to one side of the platform, said lever extending substantially horizontally and being movable up and down to control the truck.

2. The combination in a freight truck, of a platform at one end thereof upon which the operator stands, and two operating levers pivoted to the truck above the platform, one of said levers being at one side and the other at the other side of said platform, said levers extending substantially horizontally and being movable up and down to control the truck.

3. The combination in a freight truck, of a platform at one end thereof upon which the operator stands, a steering lever pivoted above and at one side of the platform, a controller lever pivoted above and at the other side of the platform, said levers extending substantially horizontally and being movable up and down to control the truck.

4. The combination in an electric freight truck having a controller and a steering mechanism, of a controller lever pivoted above and at one side of the platform and connected to the controller, a steering lever pivoted above and at the other side of the platform and connected to the steering mechanism, said levers extending substantially horizontally and being movable up and down to control the truck.

In witness whereof, I have hereunto set my hand this eighth day of September, 1913.

ROBERT McA. LLOYD.
